His ATTORNEY

UNITED STATES PATENT OFFICE.

MURREL O. DEVERS, OF DAYTON, OHIO.

DIM-BRIGHT SWITCH FOR ELECTRIC SYSTEMS.

Application filed March 10, 1921. Serial No. 451,269.

To all whom it may concern:

Be it known that I, MURREL O. DEVERS, a citizen of the United States, residing in the city of Dayton, in the county of Montgomery and State of Ohio, have invented certain new and useful Improvements in Dim-Bright Switches for Electric Systems, of which the following is a specification.

The principal object of my invention is to provide a dim-bright switch for attachment to motor-cycle handle bars, or to the steering wheels of automobiles, to enable the driver to control the lights without releasing his hand from the handle bar or wheel.

10 The device is simple in construction and efficient in operation. It is compact in appearance, and may be readily attached to a handle bar or steering wheel for convenient operation.

15 In the accompanying drawings, Figure 1 is a top plan view of my improved switch, with the cover removed, in a lighting system. Figure 2 is a longitudinal section taken through said switch. Figure 3 is a cross sectional view thereof, taken on the line a—a of Figure 2. And Figure 4 is a perspective view of said switch.

Throughout the specification and drawings, similar reference characters denote corresponding parts.

20 Referring to the accompanying drawings, the numeral 1 designates a switch base preferably constructed of a phenolic condensation product. Provided in the top portion of said base is a longitudinal groove 2, which extends from one end thereof to a point near its opposite end. (See Figures 1 and 2.)

25 Longitudinally movable within the groove 2 is a contact plunger 3 preferably constructed of a phenolic condensation product and terminating at its front end in an up-turned finger-grip portion 4.

30 Secured to the switch base 1, by screws 4^a, 4^a, on one side of the groove 2 near the rear end of said base, is a right-angled contact piece 5 whose transverse end 6 projects a substantial distance over said groove. Secured by screws 7, 7 to said base is a similar contact piece 8 whose transverse end 9 projects over the groove 2 to a substantial distance. The contact pieces 5 and 8 are so secured to the switch base 1 that a slight space is left between their transverse ends. (See Figure 1.)

35 Secured by screws 10, 10 to the switch base 1 on the opposite side of the groove 2

therein, is a contact piece 11 which has a right-angled end 12 that projects downwardly into said groove. (See Figures 1 and 3.)

40 Fitted on the rear end of the plunger 3 is a channeled contact piece 13 whose middle portion is so cut away as to provide a wide band 14 on one end and a narrow band 15 on its other end. (See Figures 2 and 4.) The space between these band portions of the contact piece 13, is wider than that occupied by the adjacent transverse ends of the contact pieces 5 and 8 on the switch base 1, for a purpose to be hereinafter described.

45 Projecting through the switch base 1 into a longitudinal groove 16 in the bottom of the plunger 3, is a screw 17 whose upper end, by engaging the end of the grooved portion 16 of said plunger, will limit the outward movement of the latter. (See Figures 2 and 3.) A cupped cover 18 having a sloping front end, preferably constructed of a phenolic condensation product, is secured by screws 19, 19 to the switch base 1.

50 Referring to Figure 1, the numeral 19^a designates a reflector casing in which is mounted a bright electric lamp 20 and a dim electric lamp 21. A wire 22 has one of its ends connected to the lamp 20, and its other end connected to the contact piece 5 by one of the screws 4. Connected to the contact piece 8 by one of the screws 7, is one end of a wire 23 whose other end is connected to the dim light 21. Connected by one of the screws 10 to the contact piece 11, is one end of a wire 24, whose other end is connected to a battery 25 from which a wire 26 leads to the ground. Since the flanged end 12 of the contact piece 11 is always in engagement with one side of the contact piece 13 on the plunger 3, an electric circuit will be closed from the battery to the dim lamp 21 when the transverse end of the contact piece 8 engages the narrow band 15 on the plunger, and to both lamps when both transverse ends of the contact pieces 5 and 8 are engaged by the wide band 14 on said plunger.

55 In operation, when the plunger 3 is moved to the position shown in Figure 1, the two adjacent transverse ends of the contact pieces 5 and 8 will be between the band portions 14 and 15 of the contact piece 13 on the plunger. Since in this position of the plunger, the contact piece 13 thereon does not touch either one of the contact pieces 5 or 8, no current can flow from the

battery to the lamps. Now, when it is desired to light the dim light 21, the plunger is pushed inwardly a sufficient distance to bring the narrow band portion 15 of the 5 contact piece 13, under the transverse end 9 of the contact piece 8, whereupon a circuit will be closed through the dim light 21 to illuminate it. On the other hand, when it is desired to light both lamps 20 and 21, 10 the plunger 3 is pulled outwardly a sufficient distance to bring the wide band portion 14 of the contact piece 13 under the transverse ends of both contact pieces 5 and 8, whereupon an electric circuit will be 15 closed through both of the lamps 20 and 21 to illuminate them.

I do not wish to be limited to the details of construction and arrangement herein shown and described, and any changes or 20 modifications may be made therein within the scope of the subjoined claim.

Having described my invention, I claim:

An electric switch of the type specified, comprising a base made of insulating ma-

terial and having a longitudinal groove in 25 its upper portion, of a pair of contact pieces secured to said base, ends on said contact pieces projecting transversely over said groove, a plunger constructed of insulating material, movable in said groove, a channeled 30 contact member fitted on said plunger, a contact element secured to said base, having a portion projecting into said groove for contact with one side of said channeled member, a band portion on each end of said 35 channeled member, with a space left between said band portions wider than that occupied by the transverse ends of the contact pieces on the switch base, said plunger adapted to be moved to bring one band 40 portion under one of said contact pieces, and the other band portion under both of said contact pieces, for the purpose specified.

In testimony whereof I have hereunto set my hand this 3rd day of March, 1921.

MURREL O. DEVERS.

Witness:

HOWARD S. SMITH.
